WILLIAM H. GOODALE, OF COLTON, NEW YORK.

Letters Patent No. 88,031, dated March 23, 1869.

IMPROVEMENT IN MAKING CONE SPRINGS.

The Schedule referred to in these Letters Patent and making part of the same.

To all whom it may concern:

Be it known that I, WILLIAM H. GOODALE, of Colton, in the county of St. Lawrence, and State of New York, have invented a new and improved Former for Making Upholstering Cone Springs; and I do hereby declare that the following is a full, clear, and exact description thereof, which will enable others skilled in the art to make and use the same, reference being had to the accompanying drawings, forming part of this specification, in which—

Figure 1 is a front view of my improved machine.

Figure 2 is a top view of the same, part being broken away, to show the construction.

Figure 3 is a side view of one of the springs.

Figure 4 is a detail top view of the same.

Similar letters of reference indicate like parts.

My invention has for its object to furnish an improved machine for forming or turning upholstering cone springs, which shall be simple in construction, and effective in operation, forming the springs quickly and accurately; and

It consists in the construction and combination of the various parts, as hereinafter more fully described.

A is the main frame of the machine, to which are attached the bed-plate B and die C, by which the upper end of the spring D is formed.

E is the vertically-sliding frame, which slides up and down in guides in the frame A.

The cross-bar e' of the frame E acts as a follower for "setting," or forming the spring in the die, or holder, C.

F is a cone, upon the base of which is formed or to it is attached a journal which works in bearings in the frame A, and to the rearwardly-projecting end of which are attached a crank, G, or a pulley, by means of which the said cone F is revolved, and a ratchet-wheel and pawl, by which the said cone may be held securely in place, and prevented from being drawn back by the tension of the wire.

The conical surface of the cone F is grooved spirally in exactly the form of the required spring.

The forward end of the spiral groove of the cone F terminates in a longitudinal groove formed in the cylindrical forwardly-projecting part of the said cone, which said groove is made so deep, that when the vertical upper end of the spring D is placed in it, the said upper end of the said spring may be exactly in the axis of the cone F.

In the base of the cone F, at the rear end of the spiral groove in said cone, is secured a knife, or cutter, H, upon which the wire is cut off by the descent of the cutter I, formed upon or attached to the outer, or free end of the lever J.

The lever J is pivoted to the frame A, and its rear end is held down, holding the cutter I away from the cone F by the spring K, which is attached to the frame A, and the free end of which rests upon the end of the lever J, as shown in fig. 1.

L is a lever, which is pivoted to the frame A, in such a position that its inner end may rest against the inner end of the lever J, as shown in fig. 1.

M is a connecting-rod, the upper end of which is attached to the outer end of the lever L, and the lower end of which is attached to the treadle, or foot-lever N, which is pivoted to the frame A, in such a position that its outer, or free end may be conveniently reached and operated by the operator with his foot.

P is a cylindrical reduced portion of the top cross-bar of the frame A. This projection, or tube, P, is perforated longitudinally in its outer end, and, in using the machine, one end of the wire, from which the spring is to be formed, is inserted therein, and the same bent to form a right angle.

The straight, or vertical upper end of the spring D is then inserted in the longitudinal groove in the cylindrical forward end of the cone F. Then, by revolving the cone F, by means of the crank G, the wire will be wound around the cone F, following the spiral groove of said cone, and thus receiving the desired form. As the wire reaches the rear end of the said spiral groove, the operator, by pressing down upon the treadle N, cuts it off, when the formed spring may be removed from the cone, and the upper vertical end, which has been previously bent by means of the tube P, is inserted in the perforation in the cross-bar e', as shown in red.

The lower, or enlarged part of the spring D, is also placed in the cavity e in the holder C; and in order that the spring may be held firmly, or prevented from turning, the lower end of the wire, or spring, is placed in contact with the shoulder d formed in the cavity e of the holder C. It will be understood that, for the purpose of arranging the spring in this position, the frame E is adjusted so as to bring the cross-bar e' at a proper distance from the holder C.

The operation is now completed by the operator pressing, with his foot, upon the lower cross-bar of the frame E, whereby the middle and parallel cross-bar e' is pressed down upon the spring D, and the same "set," or caused to assume the desired shape.

When formed in this way, the upper, or vertical end of the spring D will be exactly in the axis of said spring, so that pressure applied to said vertical end will bear equally upon all parts of said spring, and compress it vertically and equally.

Having thus described my invention,

I claim as new, and desire to secure by Letters Patent—

The improved apparatus for forming upholstering cone springs, consisting of a die, or holder, C, frame A, vertical-sliding frame E, tube P, spirally-grooved cone F, cutters H and I, lever J, spring K, level L, connecting-rod M, treadle, or foot-lever N, and ratchet and pawl, all constructed and arranged upon the frame, substantially as herein shown and described, and for the purposes set forth.

WILLIAM H. GOODALE.
